Fig. 6.

A detailed technical line drawing of a mechanical assembly, possibly a gear train or a motor. The drawing shows a complex arrangement of gears, shafts, and structural elements. Numerous components are labeled with numbers: 3, 9, 25, 39, 41, 37, 31, 32, 17, 1450, 18, 20, 22, 23, 24, 59, 1, 51, 15, 16, 19, 31, 33, 38, 42, 29, 30, 34, 35, 36, 38, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, UNITED STATES PATENT OFFICE.

JOHN C. BARCLAY, OF NEW YORK, N. Y.

PRINTING-TELEGRAPH.

SPECIFICATION forming part of Letters Patent No. 787,608, dated April 18, 1905.

Application filed July 9, 1904. Serial No. 215,916.

To all whom it may concern:

Be it known that I, JOHN C. BARCLAY, a citizen of the United States, residing at New York, in the county of New York and State 5 of New York, have invented certain new and useful Improvements in Printing-Telegraphs; and I do hereby declare the following to be a full, clear, and exact description of the invention, such as will enable others skilled in the 10 art to which it appertains to make and use the same.

My invention relates to improvements in printing-telegraphs, and embodies means whereby motor-driven printing mechanism is 15 controlled by suitable electric selecting mechanism, so as to print at will any desired character within the capacity of the machine or to space, to return the carriage, or to feed the paper.

20 My invention comprises electrically-operated means controlling clutch mechanism interposed between a driving member and the printing mechanism, electrically-operated mechanism determining the selection of the 25 character to be printed by the printing mechanism, electrically-operated shift mechanism, electrically-operated carriage-return mechanism, and electrically-operated paper-feed mechanism.

30 The printing-telegraph herein described further involves the electrical selecting mechanism set forth in my Patent No. 758,732, dated May 3, 1904, also other features of invention set forth in my Patent No. 785,076, 35 dated March 21, 1905.

The objects of my invention are to increase 40 the speed of operation of printing-telegraphs, to render the same more certain and reliable in operation, and to render the same more 45 simple, compact, and durable and lighter running.

I will now proceed to describe my invention with reference to the accompanying drawings and will then point out the novel features 45 thereof in claims.

In the said drawings, Figure 1 shows an elevation of the left-hand side of the printing-telegraph receiver, the selecting-relays and associated parts being omitted. Figs. 2 to 5, 50 inclusive, are detail views of the clutch em-

ployed for transmitting motion from a power or driving shaft to the printing mechanism and of the associated parts, Fig. 2 showing a front view of the clutch and associated parts, Fig. 3 a longitudinal section thereof, Fig. 4 55 a transverse section on the line X X of Figs. 2 and 3, showing the cam mechanism for operating the carriage-feed, and Fig. 5 a transverse section in the line Y Y of Figs. 2 and 3 through the center of the clutch, showing the 60 device for opening and closing the clutch. Fig. 6 shows a sectional elevation of the machine, the section being taken on planes parallel to Fig. 1 and in such manner as to disclose the operation of the printing mechanism. Fig. 7 is a detail view showing in side elevation the type-wheel shift mechanism. Fig. 8 shows a front view of the printing mechanism of the machine, the carriage return and shift magnets being omitted. Fig. 70 75 9 is a detail view showing one of the type-wheel-actuating pawls and the rod for actuating the same. Fig. 10 shows an elevation of the side of the machine opposite that shown in Fig. 1. Fig. 11 shows a rear elevation of 75 the machine. Fig. 12 shows a detail front view of the carriage return and shift magnets and the parts operated thereby. Fig. 13 shows a detail top view of the paper-carriage. Fig. 14 is a detail top view showing the arrangement of the printing-magnets. Fig. 15 is a diagrammatic view showing the combination of selecting-relays and co-operating devices whereby by the transmission of proper signals any particular operating-magnet of the 85 machine may be selected, energized, and caused to operate the mechanism controlled thereby.

I will first describe the printing mechanism and associated parts of the machine, including 90 the magnets and associated parts by which the operation of the machine is effected, and will then describe with reference to Fig. 15 the preferred arrangement of selecting devices to be employed in connection with the 95 machine.

The printing mechanism which I prefer to employ and which is illustrated in the drawings is of the type in which power for moving the type to the printing-point and for 100

making the impression is supplied by a constantly-rotating power or driving shaft, the determination of the particular character from which the impression is to be taken being effected under the control of electrical selecting mechanism by mechanical devices capable of operating with extreme rapidity and requiring a minimum of power for their operation. The particular printing mechanism shown is in substance that of a known type of power-driven type-writer with the finger-keys removed; but I do not limit myself to the use of this particular mechanism.

In the machine shown power for the operation of the machine is derived from a power-shaft 1, Fig. 1, which is continuously driven by means of an electric motor located within the casing 2. The machine is of the type-wheel type, embodying a type-wheel 3, having on its periphery a plurality of characters which may be brought into printing position by rotating said wheel more or less and also when necessary by moving the wheel axially. Rotation of this type-wheel and the striking of the blow necessary for the making of an impression is effected by power derived from the driving-shaft 1 through the agency of a clutch 4 5 on said shaft. Said clutch comprises two jaw members 4 and 5, of which the former is fast on said shaft and the latter is longitudinally movable thereon and by means equivalent to a spline is in driving connection with a cam 6 (see Fig. 6) on said shaft. A spring 7 tends to press the two clutch members together; but this is prevented normally by a spacing-piece 8, Fig. 5, engaging the movable clutch member 5, which spacing-piece is arranged to be withdrawn when a magnet 9, hereinafter termed the "spacing-magnet," is energized, the means for so withdrawing said spacing-piece comprising the armature 10 of said magnet, the rocker-arm 11, connected thereto, and the link 12, connecting the rocker-arm and the spacing-piece 8, which latter is itself supported by the rocker-arm 13.

Cam 6 when rotated through the closing of clutch 4 5 pushes to the right of Fig. 1 a bar 14, supported by links 15 and 16 and arranged to transmit motion through a leaf-spring 17 (shown in dotted lines in Fig. 1) to a swinging transverse actuating-bar 18. In rear of this actuating-bar there are a plurality of gear-segments 19, one for each division or character-space of type-wheel 3, and each of said segments carries a corresponding pawl 20, normally above and out of engagement with the main actuating-bar 18 and held out of such engagement by a spring 21, but arranged to be drawn down into such engagement at suitable times by a corresponding operating-rod 22, mounted to slide up and down in suitable guides at the front of the machine and connected each to the armature-lever 23 of the corresponding printing-magnet 24, the completion of the circuits of

these printing-magnets being controlled by the electrical selecting mechanism shown in Fig. 15 and hereinafter described. It will be apparent, however, that when any one of the printing-magnets 24 is energized its corresponding pawl 20 will be drawn down into engagement with the actuating-bar 18, and since, as hereinafter explained, at the same instant when any printing-magnet 24 is energized the spacing-magnet 9 is also energized, and the clutch 4 5 is thereby closed and the cam 6 caused to revolve and move the actuating-bar 18 forward, it follows that as soon as any one of the pawls 20 engages the bar 18 it and its gear-segment 19 are drawn forward, the effect of which, as will now be explained, is to rotate the type-wheel to the proper amount and then to cause it to move backward bodily to make the impression. The said type-wheel 3 is mounted upon a spindle 25, said spindle being mounted in a support 26, carried by a transverse rocker-shaft 27, having its bearings in the frame of the machine. The type-wheel and spindle are in driving connection by means hereinafter described. Upon the shaft 27 are mounted loosely two sleeves 28, one to the right and the other to the left of the support 26, of which only one is shown in Fig. 6. The said sleeves carry gear-sectors 29, intermeshing with a pinion 30 on the spindle 25. Upon the sleeves 28 are mounted a plurality of segmental gears or tumblers 31, each corresponding to and in mesh with one of the gear-segments 19, above mentioned. These tumblers 31, though mounted on sleeves 28, are normally out of driving connection therewith, each tumbler being normally in an eccentric position with respect to its sleeve 28, but being mounted upon such sleeve in such manner as to be capable of sliding into the concentric position. The first effect of the motion of the gear-sector 19 is to cause its corresponding tumbler 31 to move to the right of Fig. 6 until the locking projection 32 of the sleeve 28 is in engagement with the locking-recess 33 of that tumbler. In this position the tumbler and sleeve 28 are concentric. Thereafter the tumbler and sleeve rotate together and by their rotation rotate the corresponding gear-sector 29, the pinion 30, and spindle 25, and therefore the type-wheel 3.

It is obviously necessary that the movement of some of the gear-sectors 19 should produce only a small angular movement of the type-wheel about its axis, while the movement of others of said gear-sectors 19 should cause said type-wheel to move through a much greater angular distance. It is also desirable that the total movement of all the gear-sectors 19 should be the same. This may be accomplished in various ways, one of the most convenient of which is to graduate the pitch-diameters of the several sectors 19 and their respective tumblers in such manner that although all the gear-sectors 19 move through

- the same distance the tumblers 31 move through different distances corresponding to the particular angular distance through which each tumbler should move the type-wheel to bring the corresponding character into printing position, the tumblers which rotate the type-wheel through relatively great angles being of less diameter and their respective segments 19 being of greater diameter than the tumblers and segments which move the type-wheel through less angles. It will be seen that by properly proportioning and graduating the diameters of the several tumblers 31 and the gear-sectors 19 by which they are operated the several angular movements of the type-wheel required to bring any particular character thereon into printing position may be produced notwithstanding that all the gear-sectors 19 move through the same distance.
- 20 The several tumblers are arranged to pick up a transverse bar 35 when their corresponding characters on the type-wheel are in approximately the printing position, and this transverse bar 35 when picked up causes a stop-pawl 36 to engage one of the teeth of a stopping-ratchet 37, carried by the pinion 30, thus arresting the rotative movement of the type-wheel with the desired character opposite the platen. This locking of the type-wheel occurs before the forward movement of the transverse actuating-bar 18 is completed, and such movement of the actuating-bar continuing and the type-wheel being no longer able to rotate the pivoted support 26 of said type-wheel is caused to move backward about the shaft 27 as an axis, carrying the type-wheel with it and causing said type-wheel to strike a blow against the platen 38 or upon a piece of paper carried thereby.
- 25 In its backward movement the character opposite the platen wipes past an inking-roller 39, and therefore the striking of this character against the platen or paper thereon gives the desired impression. The cam 6 on the driving-shaft 1, by which motion is imparted to the actuating-bar 18 and thence to the type-wheel, is of such shape that in the first instance it gives a gradually-accelerated motion to said actuating-bar and then before the type-wheel reaches the platen permits said bar 18 to move forward by inertia in advance of the motion of the cam, so that the blow is struck by momentum. A stationary cam 40 engages a projection 40' on clutch member 5 when said member has nearly completed its revolution, and said projection riding upon cam 40 is forced to the left of Fig. 2, carrying with it the clutch member 5, and so opening the clutch. Just before the clutch member 5 comes to rest it slips off the end of cam 40 and comes to rest on the spacing-piece 8, which forms a continuation of cam 40 and has a lug 8', forming a stop for projection 40'. The spacing-piece therefore holds the clutch open until upon magnet 9 being energized
- link 12 and said spacing-piece are again drawn forward, permitting the clutch member 5 to move again into engagement with clutch member 4. It will be seen, therefore, that each time one of the magnets 24 is energized, 70 and with it the magnet 9 and the link 12 and spacing-piece 8 are drawn forward, the clutch 4 5 is closed for one revolution only of cam 6, and then the clutch is opened, thus preventing repetition of the character corresponding to 75 that magnet 24 unless the same magnet be energized again.
- Link 12 is not directly connected to arm 11, actuated by the magnet 9, but is supported by a pivot 12', Fig. 1, and by the arm 13 80 and spacing-piece 8, above referred to, and motion is transmitted from arm 11 to link 12 through a pin 153. Arm 11 and link 12 have independent retractile springs 154 and 155, respectively, which return them to normal as 85 soon as magnet 9 is deenergized, and to further insure the return of spacing-piece 8 and link 12 to normal before the projection 40' reaches the end of cam 40 said spacing-piece has a horn-like extension 156, Fig. 5, which 90 will be engaged by a pin 157, carried by the clutch member 5 and forced back if said spacing-piece has not already reached its normal position before pin 157 comes opposite said extension. As soon as cam 6 permits upon the 95 completion of its revolution parts 14, 15, 16, and 18 are returned by a retractile spring 158, Fig. 6, connected to an arm 159, secured to rock-shaft 160, upon which the arm 16 is loosely mounted and to which spring 17 and 100 actuating-bar 18 are secured. The type-wheel and associated parts are returned to normal by a spring 161, Fig. 1, connected to an arm 162, engaging a cam or finger 163 upon the transverse rocker-shaft 27.
- 105 The tumblers 31, each corresponding to a different character of the type-wheel, constitute selecting devices of the printing mechanism each adapted for bringing its corresponding character into operative position for printing.
- Upon the spindle 25 of the type-wheel 3 there is a star-wheel 41, which when the type-wheel begins to move backward to strike an impression is engaged by a centering-pin 42, 110 which serves to bring the character to be struck into the exact position required to give a good impression.
- Carriage-feed.—For letter-spacing and spacing between words the carriage carrying 115 the platen is free to move to the right or left, as in ordinary type-writers. It is fed to the left for spacing between letters and between words by a cam 43, Figs. 2, 4, and 11, on drive-shaft 1 and controlled by clutch 4 5, 120 which is both a face-cam and an edge cam. The face or side of this cam works against a claw-lever 44, pivoted to move in the direction of motion of the carriage and also pivoted to move slightly in a plane substantially at right 125
- 130

angles, so as to move into and out of engagement with a rack 45 on the back of the carriage. Normally the claw-lever 44 is out of engagement with the rack, and its upper end 5 is in the extreme right-hand position looking from the front of the machine or in the extreme left-hand position looking at the rear of the machine, being held in such position and out of engagement with the rack by a 10 suitable retractile spring 46. The face portion of cam 43 causes said claw-lever when the cam rotates to move to the right of Fig. 11 through a distance equal to a single space, and at the same time the edge of cam 43, acting 15 on the follower 47, connected to said claw-lever, causes the latter to engage the rack 45, so that the claw-lever in its lateral movement carries the carriage with it. As soon as such lateral movement is completed 20 the edge portion of the cam 43 permits the claw-lever to fly back to its original position.

As will be explained hereinafter in the description relating to Fig. 15, the circuits in which the several printing-magnets 24 are located have a common return, in which the spacing-magnet 9 is located, so that the magnet 9 is energized and the clutch closed each time one of the printing-magnets is energized. As will also appear from the description relating to Fig. 15, the selecting mechanism is arranged to complete the circuit through the spacing-magnet 9 independent of the printing-magnets 24 when it is desired to space, but not to print. It will be obvious that if 25 the magnet 9 is energized without any of the printing-magnets 24 being energized simultaneously the clutch 45 will be closed and the spacing mechanism just described will be operated and the carriage moved to the left one 30 space even though no portion of the printing mechanism operates. In such case the actuating-bar 18 moves forward idly, none of the pawls 20 engaging it.

Carriage-return.—For returning the carriage to the right-hand or starting position a magnet 49, Figs. 10 and 12, is provided on front of the machine. The armature 50 of this magnet engages a lever 51 and depresses said lever when the magnet is energized. Depression of this lever 51 has the effect of drawing a friction-wheel 52 on a shaft 53 into engagement with a friction-wheel 54, arranged to be driven continuously by the motor of the machine. Such movement of the shaft 53 is 55 permitted, owing to the fact that the bearing 55 of said shaft is arranged to have a slight oscillating movement. When wheel 52 is so drawn into frictional engagement with wheel 54, it drives bevel-gears 56 and 57 and a pinion 58, which pinion engages the rack 45 on the back of the carriage, the effect of such rotation of the pinion being to move the carriage by power derived from the motor back to the starting-point.

65 As will be described hereinafter with refer-

ence to Fig. 15, means are provided for preventing the energization of any of the printing-magnets or the spacing-magnet 9 while the carriage is moved back to the starting-point.

Paper-feed.—For feeding the paper—i. e., for line-spacing—a magnet 59 is provided. (See Figs. 10 and 11.) This magnet may be located conveniently at the back of the machine. Its armature 60 is connected, through 70 a link 61, with one arm of a bell-crank 62. The other arm of this bell-crank is connected to a link 63, having in it an aperture through which passes freely a rod 64, mounted to oscillate about an axis substantially concentric with that of the platen 38 and having connected to it a pawl 65, engaging a ratchet 66 on the platen. The connection is such that the rod 64 is free to move to the right or left with the carriage, sliding through the orifice in link 63; but nevertheless whenever magnet 59 is energized said rod 64 will be drawn down and the pawl 65 be caused to engage the ratchet-wheel 66, and so rotate the platen to 75 line-space.

Type-shift.—The type-wheel 3, as already stated, is provided with two bands of characters, of which normally the upper band only is in the printing position. The spindle 25 of the type-wheel is capable of longitudinal movement within its support 26, the effect of such longitudinal movement being to move the lower band of characters on the type-wheel in the printing position. Such movement may be effected by means of the following mechanism: The lower end of the spindle 25 rests upon an arc-shaped portion 67 (see Fig. 7) on an arm 68, such arc-shaped portion being substantially concentric with the shaft 27. This arm 68, however, is arranged to be moved upward, and thereby to move the type-wheel upward by means of a link 69, connected to a bell-crank 70, which bell-crank is connected by another link, 71, Fig. 12, to the armature 72 of a shift-magnet 73, which may be located conveniently at the front of the machine. The construction is such that when said magnet is energized and its armature attracted the arm 68 is raised, and with it the type-wheel, the effect being to bring the lower band of characters on said wheel into the printing position.

Selecting mechanism.—Obviously any suitable selecting mechanism may be employed for energizing any one of the printing-magnets 24 as desired; but I prefer to use the selecting mechanism set forth in my Letters Patent No. 758,732, dated May 3, 1904, and particularly the improved mechanism set forth in my Patent No. 785,076, dated March 21, 1905, because of the rapidity and certainty with which such mechanism operates. This mechanism and the various printing-magnets, together with the spacing-magnet, paper-feed magnet, the carriage-return magnet, and the type-shift 115 120 125 130 135 140 145 150 155 160 165 170 175 magnet, are shown diagrammatically in Fig. 15. For operating this selecting mechanism successive current-pulses are employed, which are the same in number for each character 5 transmitted, but vary in length, the different characters being differentiated by variations in number and arrangement of dots and dashes. For transmitting the characters of the English alphabet six pulses are employed for each 10 message or character. The printing or other magnet corresponding to each such message transmitted is selected by the action of primary and secondary selecting relays—a sunflower and a separator relay, as hereinafter 15 described. The primary actuating device of this selecting mechanism is a line-relay 74, located in the line-circuit 75. This line-relay may of course be differentially wound to permit of duplex or quadruplex operation. The 20 said relay controls two local circuits 76 and 77, connected to opposing contact-points of the main-line relay, both of which circuits pass through coils of a neutral relay 78, termed the "separator-relay," through opposing coils 25 of magnet 79, operating escapement mechanism of the sunflower hereinafter described, and through a synchronizer-magnet 98 to ground at 80. A battery 81 or other suitable source of electrical energy is connected to 30 ground and to the armature of main-line relay 74. One or the other of circuits 76 and 77 is completed through battery 81, according as the said armature of relay 74 is in contact with the right-hand or left-hand contact of 35 said relay.

The main-line relay 74 is very rapid in action and operates for each pulse produced in the main line whether short or long. The separator-relay is more sluggish in action and 40 completes the circuit which it controls only when a long pulse is sent over the line. The circuit controlled by separator-relay 78 passes from ground at 83, through battery 84, the armature of separator-relay 78, and conductor 45 85, to a plate 86 of the sunflower, to which the first five contact-points 87, 88, 89, 90, and 91 of that sunflower are electrically connected. This sunflower consists of contact-points 87, 88, 89, 90, 91, and 92, adapted to be actuated 50 successively by teeth of a ratchet-wheel 93 during movement of said wheel through the space of one tooth. Said ratchet-wheel is mounted upon a shaft 94, upon which is also mounted an escapement-wheel 95, having 55 three times the number of teeth of ratchet-wheel 93 and controlled in its movement by the escapement-anchor 96, which is actuated by the armature 97, which is polarized. The coils of magnet 79, through which circuits 76 60 and 77 pass, being oppositely wound, alternate pulses in these circuits will cause the vibration of the escapement-anchor 96, and six such pulses, permitting rotation of escapement-wheel 95 through the space of three teeth, 65 will advance ratchet-wheel 93 through the

space of one tooth, causing contact-points 87 to 92 to complete their respective contacts successively and completing one cycle of operation of the sunflower. The shaft 94 of the sunflower is driven by any suitable device, 70 such as a spring-motor or friction-drive, which will permit intermittent motion of said shaft.

Magnet 98 beneath the sunflower is a synchronizer-magnet operating an armature-lever 99, having a hook adapted to engage the 75 teeth of ratchet-wheel 93. It is not necessary herein to describe the action of this synchronizer, as it is not required for the comprehension of the operation of the selecting mechanism and, indeed, may be omitted, circuits 80 76 and 77 passing directly from the coils of magnet 79 to ground.

It was stated above that the metal frame 86, carrying contact-points 87 to 91, is connected by conductor 85, passing through contacts 85 of separator-relay 78, with battery 84 and thence to ground. These contact-points 87 to 91, inclusive, which may be termed "selector-contacts," when operated by the movement of ratchet-wheel 93 complete circuits successively from the contact-points of separator-relay 78 through conductors 100 to 104, respectively, leading to the magnets of polar selecting-relays 105, 106, 107, 108, and 109, respectively, and thence through a common return-conductor 110 to ground at 111; but it will be seen that none of these circuits through the magnets of the polar selecting-relays will be closed unless at the instant when any one of those circuits is closed through the sunflower the transmission of a long pulse through the line has caused separator-relay 78 to complete the circuit through battery 84 to ground at 83.

Polar selecting-relays 105 to 109, inclusive, 105 control circuits of secondary selecting-relays 112, 113, 114, 115, and 116, respectively, the contact-points of which are connected in tandem in the order named, the five series of contact-points forming an arithmetical progression. 110

The primary selecting-relays 105 to 109, inclusive, each control a circuit of a corresponding secondary selecting relay or relays. The controlling-circuits of these secondary selecting-relays 112 to 116, inclusive, are normally broken; but the armatures of the several primary selecting-relays are connected by a multiple-current lead 119 to a battery 120 and to ground, and when the magnet of any one primary polar selecting-relay is energized by a current passing through the sunflower and its armature is deflected said polar selecting-relay completes the circuit through the corresponding secondary selecting relay or relays which 120 it controls, thereby operating the same.

The armatures of the primary or polar selecting-relays 105 to 109, inclusive, tend to remain in contact with whatever contact-point they are in contact at the time. These relays 130

are provided with a second or restoring circuit 122 passing in series through all of these relays, which circuit when completed by a restoring-relay hereinafter mentioned returns 5 the armatures of all these relays to their normal positions, breaking the circuits of the secondary selecting-relays 112 to 116, inclusive. This restoring-circuit 122 is arranged to be completed by a restoring-relay 123 after circuit 10 is completed through the sixth contact-piece 92 of the sunflower, as hereinafter described.

Referring now to the secondary selecting-relays 112 to 116, the armature of relay 112 15 is connected to a circuit 124, arranged to be connected, through the sixth contact 92 of the sunflower, to a battery 125 and thence to ground at 126. The contacts of the secondary selecting-relays are connected in tandem 20 as follows: Relay 112 has two contact-points connected by conductors 128 and 129, respectively, to movable contacts on the armature of relay 113. Each of these movable contacts of relay 113 coacts with two contact-points, each 25 connected to a contact-point on the armature of relay 114. In like manner the fixed contact-points of relay 114 are connected each to an armature contact-point of one of the two relays 115, and so on. The fixed contact-points of relays 116 are connected to the printing-magnets 24, here shown as arranged in parallel lines, and to the spacing-magnet, the carriage-return magnet, the line-shift magnet, and the paper-feed magnet.

35 It will be seen that by means of the various secondary selecting-relays 112 to 116, inclusive, any one of the various magnets 24 may be selected at will for the completion therethrough of an energizing-circuit. This is 40 the circuit of conductor 124 and is completed and the particular magnet selected is energized upon the closing of the sixth sunflower-contact 92. In like manner the spacing-magnet 9, the carriage-return magnet 49, the paper-feed magnet 59, and the type-shift magnet 73 may be selected and the circuit completed therethrough upon the transmission of 45 the selective message corresponding to each of these magnets.

50 The spacing-magnet 9 is located in a common return of the circuits leading through the several printing-magnets 24, so the said magnet is energized each time one of the printing-magnets is energized. Said spacing-magnet 55 is nevertheless arranged to be selected and a circuit completed therethrough upon the transmission of a corresponding selective message, this being necessary in order that the spacing mechanism may be operated at 60 will when no character is to be printed—as, for example, when spacing between words. I prefer to employ for the operation of the spacing-magnet alone a message comprising six dots. Such a message will not cause any 65 of the secondary selecting-relays to be ener-

gized, but will cause the sunflower to operate, and therefore will cause said sunflower upon the completion of the sixth pulse of the message to complete a circuit through conductor 124 and a back-stop of a secondary selecting-relay of each of the five series of such relays, through conductor 139, the spacing-magnet, and thence to the common return. The circuit of conductor 139 passes through contact-points, normally closed, of a spacing-cut-out 75 relay 141 and through another contact 142 of the type-wheel-shift mechanism, contact 142 being also normally closed. The spacing-cut-out relay 141 is employed, because otherwise circuit would be closed through the sixth sunflower-contact and the back contacts of the secondary selecting-relays to the spacing-magnet 9 upon the return of the armatures of the said secondary selecting-relays to normal after the transmission of each character. 80 This spacing-cut-out relay 141 is connected in multiple with restoring-relay 123 in a circuit closed by the completion of the sixth sunflower-contact, and, like relay 123, relay 141 is somewhat sluggish, so much so that upon 85 the transmission of a message consisting only of dots it permits the circuit of magnet 9 to remain closed long enough for the operation of the spacing mechanism, but nevertheless breaks said circuit of magnet 9 after the transmission of any signal which causes the operation of one or more of the secondary selecting-relays before, through the operation of the restoring-relay 123, the armatures of said secondary selecting-relays can have reached 90 their back-stops.

Carriage-return.—It is important that during the return of the carriage the carriage-return magnet 49 shall not be deenergized through the operation of the restoring-circuit 105 122 and the restoring-relay 123 until the carriage has returned to its extreme right-hand position or starting-point. Accordingly I provide the armature 50 of the carriage-release magnet with a contact-spring 134, arranged to make contact with the fixed contact 135 and cause the restoring-circuit 122 to pass through these contacts 134 and 135, as well as through the contacts of the restoring-relay, and I further provide in the circuit with 110 the carriage-return magnet 49 a contact-lever 136, normally in contact with the stop 137, but arranged to be moved mechanically out of contact with such stop 137 when the carriage has returned completely to its starting-point. It 115 will be seen that the effect of this contact mechanism is as follows: Upon the energization of the carriage-return magnet 49 the armature of said magnet is attracted, thereby breaking the restoring-circuit between contacts 134 and 135, which circuit would otherwise be completed almost immediately through the operation of the restoring-relay 123 following the completion of the sixth sunflower-contact. The restoring-circuit remains broken until 120 125 130

when the carriage has reached its extreme right-hand position or starting-point said carriage mechanically operates contact-point 136, thus breaking the circuit through the carriage-release contact, permitting its armature to fall and close the restoring-circuit 122. This restoring-circuit is still closed through relay 123, since the sixth contact-point 92 of the sunflower remains closed until the first pulse 5 of the next succeeding character is transmitted, and therefore upon the deenergization of the armature of the carriage-release magnet the restoring-circuit will be completed and the primary and secondary selecting-relays 10 restored to normal position. As soon as another character is transmitted and the carriage begins its movement to the left contact between points 136 and 137 will be closed again. 15

20 *Shift mechanism.*—The armature 72 of the shift-magnet 73 is arranged to be held in its shifted position by a detent-lever 147, controlled by a magnet 148, which magnet is located in a multiple branch 139^a of the spacing-circuit 139, which branch, however, does not pass through contact 142 of the shift mechanism. This detent-lever 147 holds the armature 72 down when it has been attracted by its magnet, thus holding the type-wheel in its 25 shifted position. This continues until a proper message is transmitted to release the detent, such message being the spacing-message, which now does not affect the spacing-magnet, circuit 139 to that magnet being broken at contact 142. 30

35 The several sectors 19 of the printing mechanism are normally held in place by locking-levers 149. Each pawl 20 when drawn down trips the corresponding locking-lever, permitting the sector to be drawn forward by the forward movement of the actuating device 18. Springs 150, acting upon rods 151, tend to hold the locking devices 149 in engagement with the sectors. 40

45 The springs 21 of the pawls 20 are held apart by combs 152, and thus false operation of the machine is prevented.

164, Fig. 10, designates a motor-controlling switch, and 165 designates the contact-arm, 50 and 166 and 167 contact-points thereof. By this switch the motor within the casing 2 is started and stopped and its speed regulated.

It will be obvious that the particular printing mechanism herein illustrated and described 55 is only one of many printing mechanisms which I may use, and I do not limit myself to this particular printing mechanism.

It is obvious that my invention is susceptible to numerous variations and modifications 60 without departing from the essential principles thereof, and I do not limit myself to the particular details of construction, arrangement, and operation herein illustrated and described.

What I claim is—

1. In a printing-telegraph, the combination with a constantly - moving power member, printing mechanism comprising means, including selecting devices corresponding to different characters, for bringing selected characters into operative position, means for communicating motion from said power member to said printing mechanism, and selecting mechanism controlled by electrically - transmitted signals and determining the action of 70 said selecting devices, of means controlling the transmission of power to said printing mechanism, operated simultaneously with the operation of the printing mechanism by said selecting mechanism. 75

2. In a printing-telegraph, the combination with a constantly - moving power member, printing mechanism comprising means, including selecting devices corresponding to different characters, for bringing selected characters into operative position, means for communicating motion from said power member to said printing mechanism, and selecting mechanism controlled by electrically - transmitted signals and determining the action of 85 said selecting devices, of means controlling the transmission of power to said printing mechanism, said means operated by the selecting mechanism simultaneously with the operation of the printing mechanism thereby. 90

3. In a printing-telegraph, the combination with a constantly - moving power member, printing mechanism comprising a rotary type member and means for rotating the same and for obtaining impressions therefrom, driven 100 from said power member and including selecting devices corresponding to different characters, and selecting mechanism determining the action of the printing mechanism and controlled by electrically-transmitted signals, of 105 means controlling the transmission of power to the printing mechanism from said power member, said means arranged to be operated simultaneously with the operation of the printing mechanism by said selecting mechanism. 110

4. In a printing-telegraph, the combination with a constantly - moving power member, printing mechanism comprising a rotary type member and means for rotating the same and for striking the same against a surface to be 115 printed upon driven from said power member and including selecting devices corresponding to different characters, and selecting mechanism determining the action of the printing mechanism and controlled by electrically- 120 transmitted signals, of means controlling the transmission of power to the printing mechanism from said power member, said means arranged to be operated simultaneously with the operation of the printing mechanism by 125 said selecting mechanism.

5. In a printing-telegraph, the combination with a constantly - moving power member,

- printing mechanism comprising a rotary type member and means for rotating the same and for obtaining impressions therefrom driven from said power member, and tumblers corresponding to different characters determining the degree to which said type member is rotated, and selecting mechanism for operating said tumblers controlled by electrically-transmitted signals, of means controlling the transmission of power to the printing mechanism from said power member, said means arranged to be operated simultaneously with the operation of said tumblers by the selecting mechanism.
6. In a printing-telegraph, the combination with a constantly - moving power member, printing mechanism comprising a rotary type member and means for rotating the same and for striking the same against a surface to be printed upon driven from said power member, and tumblers corresponding to different characters determining the degree to which said type member is rotated, and selecting mechanism for operating said tumblers controlled by electrically-transmitted signals, of means controlling the transmission of power to the printing mechanism from said power member, said means arranged to be operated simultaneously with the operation of said tumblers by the selecting mechanism.
7. In a printing-telegraph, the combination with a constantly - moving power member, printing mechanism arranged to be operated therefrom, and selecting mechanism determining the action of the printing mechanism and comprising an electrically-controlled sunflower, a separator-relay, selecting-circuits, primary and secondary selecting-relays and restoring means, of means for connecting and disconnecting operatively the power member and the printing mechanism, said means arranged to be operated simultaneously with the operation of the printing mechanism by said selecting mechanism.
8. In a printing-telegraph, the combination with a constantly - moving power member, printing mechanism arranged to be operated therefrom, and selecting mechanism determining the action of the printing mechanism and comprising an electrically-controlled sunflower, a separator-relay, selecting-circuits, primary and secondary selecting-relays and restoring means, of means for connecting and disconnecting operatively the power member and the printing mechanism, said means operated by the selecting mechanism simultaneously with the operation of the printing mechanism thereby.
9. In a printing-telegraph, the combination with printing mechanism, a plurality of printing-magnets for operating the same, and selecting mechanism for determining the particular printing-magnet to be energized controlled by electrically-transmitted signals, of a power member, a transmission device for

communicating motion from the power member to the printing mechanism, and a magnet for controlling the operation of the printing mechanism from said power member, controlled by said selecting mechanism.

10. In a printing-telegraph, the combination with printing mechanism, a plurality of printing-magnets for operating the same, and selecting mechanism for determining the particular printing-magnet to be energized, of a power member, a transmission device for communicating motion from the power member to the printing mechanism, means operated thereby for effecting spacing independent of the operation of the printing mechanism, and a magnet for controlling the operation of said printing mechanism and spacing means from said power member, in circuit with each of said printing-magnets and also in a circuit arranged to be completed through said selecting mechanism independent of said printing-magnets.

11. In a printing-telegraph, the combination with printing mechanism, printing-magnets for operating the same and selecting mechanism for determining the particular printing-magnet to be energized, said magnets located in independent circuits arranged to be completed independently through said selecting mechanism and having a common return, of a power member, a transmission device for communicating power from the power member to said printing mechanism, means operated by said power member for effecting spacing independent of the operation of the printing mechanism, and a magnet controlling the operation of said spacing mechanism, in the common return of the printing-magnet circuits, and likewise in a circuit arranged to be completed through the selecting mechanism independent of said printing-magnets.

12. In a printing-telegraph, the combination with printing mechanism, printing-magnets for operating the same, and selecting mechanism for determining the particular printing-magnet to be energized, and comprising an electrically-controlled sunflower, a separator-relay, selecting-circuits, primary and secondary selecting-relays and restoring means, of a power member, a transmission device for connecting and disconnecting operatively the power member and the printing mechanism, and a magnet for operating said transmission device, controlled by said selecting mechanism.

13. In a printing-telegraph, the combination with printing mechanism, printing-magnets for operating the same, and selecting mechanism for determining the particular printing-magnet to be energized, and comprising an electrically-controlled sunflower, a separator - relay, selecting-circuits, primary and secondary selecting-relays and restoring means, of a power member, a transmission device for connecting and disconnecting op-

eratively the power member and the printing mechanism, means operated thereby for effecting spacing independent of the operating of the printing mechanism, and a magnet for operating said transmission device, in circuit with each of said printing-magnets and also in a circuit arranged to be completed through said selecting mechanism independent of said printing-magnets.

10 14. In a printing-telegraph, the combination with printing mechanism, printing-magnets for operating the same, and selecting mechanism for determining the particular printing-magnet to be energized, and comprising an electrically-controlled sunflower, a separating-relay, selecting-circuits, primary and secondary-selecting-relays and restoring means, said printing-magnets located in independent circuits arranged to be completed independently through said selecting mechanism and having a common return, of a power member, a transmission device for connecting and disconnecting operatively the power member and the printing mechanism, means operated thereby for effecting spacing independent of the operation of the printing mechanism, and a magnet for operating said transmission device, in the common return of the printing-magnet circuits, and likewise in a circuit arranged to be completed by the selecting mechanism independent of said printing-magnets.

15 15. In a printing-telegraph, the combination with a power member, an actuating device arranged to be operated thereby, a transmission device for connecting and disconnecting operatively the power member and actuating device, a plurality of tumblers, corresponding pawls, and printing-magnets each adapted when energized, to bring a corresponding pawl into engagement with said actuating device, of means actuated by said pawls when themselves operated by said actuating device, for operating their corresponding tumblers, printing means operated by the tumblers and adapted to print a character corresponding to whichever tumbler is operated, and a magnet controlling said transmission device.

20 16. In a printing-telegraph, the combination with a movable actuating device, means for driving the same, a plurality of pawls adapted to engage said actuating device, but normally disengaged therefrom, printing means, and means for operating the same actuated by the several pawls, of printing-magnets, armatures therefor, and sliding rods connected to said armatures and mounted to move in proximity each to a corresponding pawl, and each provided with means for engaging its corresponding pawl and moving the same into engagement with said actuating device.

25 17. In a printing-telegraph, the combination with a movable actuating device, means

for driving the same, a plurality of pawls adapted to engage said actuating device, but normally disengaged therefrom, springs normally holding said pawls out of such engagement, and combs for said springs, of printing-magnets, and means operated thereby for drawing the several pawls into engagement with said actuating device, printing means, and means for operating the same actuated by the several pawls.

30 18. In a printing-telegraph, the combination with a movable actuating device, means for driving the same, a plurality of pawls adapted to engage said actuating device, but normally disengaged therefrom, springs normally holding said pawls out of such engagement, sliding rods for actuating the several pawls, guide-bars therefor, and printing-magnets and means operated thereby for operating the several rods.

35 19. In a printing-telegraph, the combination with printing mechanism, a plurality of printing-magnets for operating the same, selecting mechanism for selecting the particular printing-magnet to be energized, a sliding carriage, and means for feeding the same during the printing, of a power-shaft, carriage-return mechanism adapted to be operated thereby but normally disengaged therefrom, a carriage-return magnet likewise controlled by said selecting mechanism, and means actuated by said carriage-return magnet for operatively connecting the carriage-return mechanism and power-shaft.

40 20. In a printing-telegraph, the combination with printing mechanism, a plurality of printing-magnets for operating the same, selecting mechanism for selecting the particular printing-magnet to be energized, a sliding carriage, and means for feeding the same during the printing, of a power-shaft, carriage-return mechanism adapted to be operated thereby but normally disengaged therefrom, a carriage-return magnet located at the front of the machine in front of said printing mechanism, said magnet likewise controlled by said selecting mechanism, an armature for said magnet, and a lever operated thereby, connected with said carriage-return mechanism and arranged to bring the same into operative engagement with said power-shaft.

45 21. In a printing-telegraph, the combination with printing mechanism, printing-magnets for operating the same, selecting mechanism determining the action of the printing-magnets, and comprising an electrically-controlled sunflower, a separator-relay, selecting-circuits, primary and secondary selecting-relays and restoring means, a sliding carriage, and means for feeding the same during the printing, of a power-shaft, carriage-return mechanism adapted to be operated thereby but normally disengaged therefrom, a carriage-return magnet likewise controlled by said selecting mechanism, and means actuated by

said carriage-return magnet for operatively connecting the carriage-return mechanism and power-shaft.

22. In a printing-telegraph, the combination with a carriage, adapted to be moved back and forth during the operation of the machine, ratchet-operated paper-feed devices thereon, and a rod for operating said paper-feed, located upon said carriage in a position substantially parallel to the direction of motion of the carriage, of a paper-feed magnet, printing mechanism, printing-magnets therefor, selecting mechanism determining the action of the printing and paper-feed magnets, and comprising an electrically-controlled sun-flower, a separator-relay, selecting-circuits, primary and secondary selecting-relays and restoring means; and means operated by the paper-feed magnet for operating the said rod on the carriage.

23. In a printing-telegraph, the combination with a type-wheel provided with a plurality of rows of characters and movable axially and rotatively, and likewise movable bodily for forming the impression, printing mechanism for rotating said wheel to bring the desired character opposite the printing position, printing-magnets for operating said printing mechanism, a shift-magnet, and means operated thereby for moving said type-wheel axially comprising means for permitting the bodily movement of said wheel by which the impression is given, of selecting mechanism for

determining the action of said printing and shift magnets, comprising a separator-relay, 35 selecting-circuits, primary and secondary selecting-relays and restoring means.

24. In a printing-telegraph, the combination with a constantly-moving power member, printing mechanism comprising means, including selecting devices corresponding to different characters, for bringing selected characters into operative position, and means, including a clutch, for communicating motion from said power member to said printing 45 mechanism, of a plurality of printing-magnets, each corresponding to and arranged to bring into operation one of said selecting devices, and another magnet and clutch-closing means operated thereby to close said clutch. 50

25. In a printing-telegraph, the combination of a constantly-moving power member, a clutch driven thereby, printing mechanism, and means for driving the same driven from said clutch, of means normally holding the 55 clutch open, a releasing member arranged when operated to permit said clutch to close, and an electromagnet operating said releasing member.

In testimony whereof I affix my signature in 60 the presence of two witnesses.

JOHN C. BARCLAY.
